UNITED STATES PATENT OFFICE.

JOHN NEWMANN, OF BROOKLYN, NEW YORK.

SPLIT ROLLER-BEARING.

1,037,510.

Specification of Letters Patent. Patented Sept. 3, 1912.

Application filed September 11, 1911. Serial No. 648,787.

To all whom it may concern:

Be it known that I, JOHN NEWMANN, a citizen of the United States of America, residing at Brooklyn, in the county of Kings and State of New York, have invented certain new and useful Improvements in Split Roller-Bearings, of which the following is a specification.

The present invention relates to roller bearings of the type specified in my United States Letters Patent No. 969,763 and No. 1,001,673 and particularly to so called split roller bearings. The roller bearings constructed in accordance with my U. S. patents above referred to are composed of loose individual parts comprising rollers, blocks or spacers and balls borne in said blocks and resting against the free ends of the rollers.

The object of my invention is to further improve such bearing and particularly the split roller bearing, and provide means enabling me to take the split bearing box apart without requiring the disassembling or prevent the falling apart of the parts.

My invention also relates to the construction, combination and arrangement of parts as will hereinafter be fully specified and claimed.

To make my invention more clear, the same is illustrated in the accompanying drawing, in which similar reference letters denote corresponding parts and in which—

Figure 1 is an inner view of one of the bearing box sections showing the rollers and spacers locked therein in assembled position; Fig. 2 is a similar view showing the inner bushing or shell in position; Fig. 3 is a cross section on line 3—3 of Fig. 1; Figs. 4 and 5 are respectively an end view and a perspective view of an individual spacer; Fig. 6 is a longitudinal section through an individual roller; Fig. 7 is an enlarged longitudinal section through the bearing box; Fig. 8 is a cross section through the inner bushing; Fig. 9 is a part of a longitudinal section on line 9—9 of Fig. 10 showing a modified construction; Fig. 10 is an end view thereof partly in section and Figs. 11 and 12 are details thereof.

In my split roller bearing, the outer shell or box is longitudinally divided into two sections or halves *a* and *b*, which are adapted to be detachably fastened together by means of screws *c*. Each half is formed internally

with a groove *d*, in which a hardened and ground steel shell or bushing is fixed, which also is longitudinally divided into two sections or halves *e^a*, *e^b*, so that one half may be fixed in one section of the bearing box and the other in the other section of the same. For the purpose to be hereafter explained, the section line *e'* of the said bushing at each side is not made straight, but V-shaped or dove-tailed. Neither is the section line made uniform at both sides of the bushing, but at one side the slanting edges are directed inwardly and at the other side outwardly. The ends *e²* of the dove-tailed edges at one side and the central part or apex *e³* at the other side in each section of the inner bushing are made to slightly project from within the respective box sections, so as to facilitate the proper adjustment of the box sections in position on top of one another. The inner bushing, or rather, each half thereof, has on its inner circumference an annular groove *e⁴*, the surface of which is ground and which serves as a raceway for the rollers adapted to revolve thereon. At each end, the box sections *a*, *b* are provided with grooves *a'*, *b'* respectively to be filled with felt, or the like, for preventing the entering of dust into the bearing and serving to retain the lubricating oil.

The roller cage is composed of individual rollers *f*, loose blocks *g* interposed between the same, and which at the ends are formed with perforations *g'* containing balls *h* that are adapted to laterally project outwardly therefrom, so as to bear against the reduced ends *f'* of the rollers. The middle portion of the rollers is adapted to bear on the ground surface of the annular groove in the inner bushing and the shoulders formed at the ends of the said middle portion together with the lateral edges of the annular groove will act as stops preventing the rollers from leaving the said annular groove. The construction of the loose blocks and rollers is substantially the same as that in my roller bearings specified in the patents above referred to and does not require any further description. There is, however, one novel feature connected with the rollers used in the present roller bearing, which consists in that the rollers are made hollow or drawn so as to form a longitudinal and centrally ex-

tending hole f^2 . This hole need not be bored to be exact and smooth, as it only serves to reduce the weight of the roller and with split roller bearings may be utilized for the purpose to be presently explained.

In order to allow the attachment of my new roller bearing to axles or shafts without requiring any uncoupling or removal of other parts already fixed to the latter, I provide an auxiliary inner bushing or shell, which is divided into two sections or halves i^a , i^b detachably joined by screws j . This bushing is adapted to be mounted on the shaft or axle and to form an inner raceway for the rollers. The same is of hardened and ground steel and formed at its ends with flanges i' . The section line i^2 of the bushing is V-shaped or dove-tailed and made in every other respect similar to that of the outer shell e^a , e^b . The purpose of this in both cases is to afford the rollers an absolutely smooth raceway, as, no matter how exact the grinding of the surface is done, the joint of the two halves of the shells always forms an edge, by which the rollers are hindered in their free motion. When the edge is made on a straight line, the rollers encounter this obstruction on their entire length and the operation of the roller bearing often fails. By making the joint or the section line of the two halves of the outer and inner shell on a slant or V-shaped, the rollers, while revolving over the raceways, only gradually encounter the obstruction and the free motion thereof is only very little affected.

For the purpose of securing the individual parts in assembled position in each half of the box, so that the latter at any time may be taken apart and removed from the shaft, I provide members, as for instance, wires k that are adapted to be used only when it is required to temporarily lock the parts in assembled position. To this end, I also provide perforations l in the ends of the box sections a , b , in the present example, two at each end, which are arranged in alignment with the holes of the two rollers lying nearest to the adjoining edges of the box sections, so that the wires or rods k may be stuck through the said perforations and rollers locking the parts in assembled position. These wires or rods will be used only when the box is to be taken apart. It will be noticed, that when the parts are thus locked in the respective box sections a , b , there will be two blocks left unlocked or loose, which upon the taking apart of the box may fall out or remain loosely resting in the latter. However, this is not objectionable, as long as the greatest number of the parts remain in assembled position.

In the modification shown in Figs. 9 to 12, inclusive, I have shown a roller bearing for a heavy load, which is composed of rollers m and short, loose blocks n inter-

posed between the ends thereof. In this case, the free ends m' of the rollers are formed with annular spherical grooves m^2 in which bear the balls o contained in the spacers or blocks n . Such construction is used preferably with large sized bearings for heavy loads and affords much saving of material.

Since various modifications may be made without departing from the spirit of my invention by those skilled in the art, I do not wish to restrict myself to the particular construction specified and shown.

What I claim and desire to secure by Letters Patent is:

1. In a split roller bearing, a sectional outer shell or box, hollow rollers therein, individual loose blocks interposed between said rollers and members adapted to be passed through the said hollow rollers to temporarily lock the parts in assembled position in each box section.

2. In a split roller bearing, a sectional box, a sectional hardened shell fixed in said box and having on its inner circumference an annular groove the surface of which is ground and forms an outer raceway, hollow rollers having reduced ends and bearing with their middle portion on the ground surface of the annular groove in the said shell, loose blocks interposed between said rollers and serving as spacers and means adapted to be temporarily passed through the said hollow rollers to temporarily lock the parts in assembled position in each box section.

3. In a split roller bearing, a sectional box, a sectional hardened shell fixed in said box and having on its inner circumference an annular groove the surface of which is ground and forms an outer raceway, hollow rollers having reduced ends and bearing with their middle portion on the ground surface of the annular groove in the said shell, loose perforated blocks interposed between said rollers, balls borne in said perforations and projecting laterally outward to bear against said rollers and means adapted to be temporarily passed through the said hollow rollers to temporarily lock the parts in assembled position in each box section.

4. In a split roller bearing, hollow rollers having reduced and grooved ends, loose perforated blocks interposed between the said reduced ends of the said rollers and balls contained in said perforated blocks and projecting laterally outward to bear in the grooves of said rollers.

5. In a split roller bearing, a box divided into two sections each having holes in its end faces, hollow rollers in said box, loose blocks interposed between said rollers and wires adapted to be temporarily passed through the said holes of the box sections

and the hollow rollers to temporarily lock the parts in assembled position in each box section.

6. In a split roller bearing, a sectional box having holes in its end faces, a sectional hardened shell fixed in said box and having on its inner circumference an annular groove the inner surface of which is ground and forms an outer raceway, hollow rollers 10 having reduced ends and bearing with their middle portion on the ground surface of the said annular groove, loose blocks interposed between said rollers and means adapted to be temporarily passed through the said holes of the sectional box and through the said hollow rollers to temporarily lock the parts in assembled position in each box section.

7. In a split roller bearing, a sectional box having holes in its end faces, a sectional hardened shell fixed in said box and having 20

on its inner circumference an annular groove forming an outer raceway, a loose sectional and hardened shell forming an inner raceway, hollow rollers having reduced ends and bearing on one side against the said loose shell and on the outer side against the ground surface of the annular groove of the fixed shell, loose blocks interposed between said rollers and means 25 adapted to be temporarily passed through said holes of the said box sections and through the said hollow rollers to temporarily lock the parts in assembled position in each box section.

In testimony whereof I affix my signature in presence of two witnesses.

JOHN NEWMANN.
